WRITING DEVICE

Ewing M. Johnson, Chicago, Ill.

Application December 22, 1941, Serial No. 423,915

3 Claims. (Cl. 281—8)

The present invention relates generally to devices for use in writing letters, communications and other data. More particularly the invention relates to that type of writing device which is portable and comprises a board together with means for feeding a strip of paper or like flexible writing material across the top face of the board.

One object of the invention is to provide a writing device of this type which is especially designed for use in writing letters of the round robin variety and is characterized by the fact that it is both compact and simple in construction and may be manufactured at an extremely low cost.

Another object of the invention is to provide a writing device of the type under consideration in which the board is mounted in a rectangular frame and the means for feeding the strip of paper across the top face of the board comprises a supply spindle and a take-up spindle, both of which are mounted in bearings on the frame.

A further object of the invention is to provide a writing device of the type and character under consideration in which the board-surrounding or supporting frame is of novel design and construction and the spindle-supporting bearings are of the split jaw type so that the spindles may be readily snapped into place in connection with assembly of the device and also may be readily removed.

A still further object of the invention is to provide a writing device which is generally of new and improved construction and is not only rugged or durable but also extremely easy to operate.

Other objects of the invention and the various advantages and characteristics of the present writing device will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views.

Figure 1 is a perspective showing a writing device embodying the invention in its normal or operative position;

Figure 2 is a perspective showing the device in an inverted position and illustrating in detail the arrangement of the supply and take-up spindles and the split jaw type bearings for releasably supporting the two spindles;

Figure 3 is a perspective showing the board and frame in an inverted position and illustrating the take-up spindle in separated relation with the frame and after the paper strip has been wound thereon; and

Figures 4 and 5 are longitudinal and transverse sections of the device, respectively.

The writing device which is shown or illustrated in the drawings constitutes the preferred embodiment of the invention. It is of unitary design or construction and has special use or utility in writing letters of the round robin type. As its main or principal parts the device comprises a board 6, a frame 7, a supply spindle 8, a take-up spindle 9 and a long strip 10 of paper or like flexible writing material.

The board 6 is rectangular and constitutes a supporting surface for the paper strip 10. It is preferably formed of plywood or like stiff material and is adapted, as hereinafter described, to have the paper strip 10 fed upwards across the top surface thereof.

The frame 7 is rectangular and serves to reinforce and support the board 6 and also to support the supply and take-up spindles 8 and 9. It consists of a pair of laterally spaced parallel side members 11, a lower cross member 12 and an upper cross member 13 and these are preferably formed of wood. The side members 11 are disposed along the side margins of the board 6 and have flat coplanar top faces. The inner upper corner portions of the side members have grooves 14 therein (see Figure 5) and these form seats for the side margins of the board. The depth of the grooves corresponds to the thickness of the board with the result that the top face of the board is flush with the top faces of the side members 11. The board and side members are held in fixed or rigid relation by coating the grooves 14 with any suitable adhesive or cement. The cross members 12 and 13 serve to cross connect the side members 11 and hold such members in spaced apart and parallel relation. The lower cross member 12 is half round, as shown in Figures 3 and 4, and is arranged so that the ends of the flat side thereof abut against the lower ends of the side members 11. Tenon and mortise joints serve rigidly to connect the lower ends of the side members 11 to the ends of the lower cross member 12 and these joints comprise tenons 15 on the lower ends of the side members and mortises 16 at the ends of the lower cross member. The upper edge of the lower cross member 12 abuts against and is flush with the bottom edge of the board 6. The upper cross member 13 is

disposed in parallel relation with the lower cross member 12 and is also half round. It is the same in size and shape as the lower cross member 12 and is arranged so that the end portions of the flat side thereof abut against the upper ends of the side members 11. Tenon and mortise joints serve rigidly or fixedly to connect the upper cross member 13 to the side members 11 and these comprise tenons 17 on the upper ends of the cross members and mortises 18 at the ends of the upper cross member. The upper edge of the upper cross member abuts against and is flush with the upper edge of the board 6. Because of the arrangement and design of the lower and upper cross members 12 and 13 the curved or round surfaces thereof are exteriorly disposed with respect to the rectangular board-supporting frame 7. The lower central portions of the side members 11 project beneath the lower edges of the cross members 12 and 13 and form flat feet 19 for supporting the frame and board on a desk, table or other supporting surface. By reason of the fact that the feet 19 are disposed beneath the lower edges of the cross members 12 and 13 the cross members are disposed in an elevated position when the feet are placed on a supporting surface (see Figure 4). The end portions of the feet 19 are upwardly beveled so that there are smooth joints between them and the outer end portions of the lower edges of the cross members.

The spindles 8 and 9 constitute the medium or instrumentality for supporting the paper strip 10 and feeding it progressively and longitudinally across the top face of the board 6. They are the same in design and construction, as shown in the drawings, and are slightly greater in length than the frame 7 is wide. The supply spindle is disposed beneath and extends transversely across the lower portion of the board 6 and has its ends releasably journaled in split jaw type substantially three-quarters round bearings 20. The central portion of the supply spindle is provided with a longitudinal slot 21 for a tab 22 on one end of the paper strip 10. When the device is assembled for initial use the tab 22 is inserted into the slot 21 and the strip is wound substantially completely around the supply spindle 8. The take-up spindle 9 is disposed beneath and extends transversely of the upper portion of the board 6 and normally is arranged in spaced apart and parallel relation with the supply spindle 8. The central portion of the take-up spindle 9 is provided with a longitudinal slot (not shown) for receiving or accommodating a tab on the other end of the paper strip 10. When the take-up spindle is in operative relation with the frame the ends thereof are journaled in a pair of axially aligned split jaw type substantially three-quarters round bearings 23 in the central portion of the side members 11 of the frame 7. The bearings 20 and 23 are formed by providing T-shaped openings 24 in the central portions of the side members 11. These openings are disposed one directly opposite the other, as best shown in Figure 3, and comprise central or intermediate entrance parts 25, lower branches 26 and upper branches 27. The lower and upper branches are longitudinally aligned with one another and extend lengthwise of the side members 11 of the frame. They communicate with the entrance parts 25 of the openings 24 and are disposed midway between the top and bottom faces of the side members 11. The lower ends of the lower branches 26 of the T-shaped

openings define the split jaw type bearings 20 for the ends of the supply spindle 8. Slots 28 are formed in the lower ends of the side member 11 and these slots extend from the bearings 20 in the direction of the lower cross member 12. Screws 29 extend transversely through the portions of the side members having the slots 28. By tightening or loosening the screws 29 the bearings 20 may be brought into any desired frictional engagement with the ends of the supply spindle 8. When it is desired to remove the supply spindle it is only necessary to shift it transversely to the center of the side members 11 and then shift it laterally through the entrance parts 25 of the T-shaped openings 24. By having the slots 28 and the screws 29 in the lower ends of the side members the bearings 20 may be adjusted so that they grip frictionally the ends of the supply spindle when the spindle is in place, and thus releasably hold the spindle in its operative position. The upper ends of the branches 27 of the T-shaped openings 24 define the bearings 23 for the ends of the take-up spindle 9. The upper ends of the side members 11 of the frame are provided with longitudinally extending slots 30 and these extend from the bearings 23 in the direction of the upper cross member 13. Screws 31 extend through the portions of the side members 11 having the slots 30 therein and together with said slots constitute means for adjustably maintaining the bearings 23 in frictional engagement with the ends of the take-up spindle 9. When the take-up spindle is in place the ends thereof are journaled in the bearings 23, as shown in Figures 1 to 4 of the drawings. To remove the spindle 9 it is only necessary to shift it transversely of the central portions of the side members 11 of the frame and then move it laterally through the entrance parts 25 of the T-shaped openings 24. The two spindles are provided with cylindrical end knobs 32 for turning purposes. By reason of the fact that the bearings 20 and 23 are three-quarters round the spindles snap into place when shifted into their operative position and tend to remain in place.

In using the device the free end of the paper strip 10 is drawn from the supply spindle 8 and is trained around the lower cross member 12 of the frame. Thereafter it is drawn across the top face of the board 6 and is trained around the upper cross member 13. After this operation the tab on the free end of the paper strip is inserted into the longitudinal groove in the central portion of the take-up spindle 9 and the take-up spindle is rotated so as to wind the free end of the strip therearound. When the device is in its operative or assembled position, as shown in Figures 1, 2 and 4, the portion of the paper strip 10 that is supported by the board 6 is available for writing purposes. When the portion of the paper strip that is supported by the board has been used the strip is advanced or fed in order to bring an unused portion of the strip into place for writing merely by turning the take-up spindle 9 in the proper direction to cause the strip to wind therearound. Turning of the spindle is effected by gripping the knob 32 on the spindle. When the take-up spindle is turned the strip is drawn upwards across the board 6 and is automatically unwound from the supply spindle 8. After one side of the paper strip has been filled with writing the other side may be used for writing merely by removing the take-up spindle 9 with the strip wrapped therearound, then shifting the empty supply spindle 8 into the

bearings 23, then manipulating the take-up spindle 9 into the bearings 20 and finally training the free end of the strip around the lower cross member 12 across the board 6 and around the upper cross member 13 and then inserting the tab 22 into the slot 21. With this particular assembly of the device the unwritten side of the paper strip 10 is exposed for writing purposes and the supply spindle becomes the take-up spindle and the take-up spindle becomes the supply spindle. After the strip has been used on both sides or on one side alone the spindle on which the strip is wound may be removed from the frame and sent to any desired destination by enclosing it in a suitable container. Should the ends of the spindles fit but loosely in their respective split jaw type bearings the bearings may be tightened by tightening the adjusting screws. By reason of the fact that the frame 7 includes the feet 19 the portions of the strip which extend between the spindles and the lower and upper cross members of the frame are spaced above the supporting surface on which the frame rests in connection with use of the device. By having such portions of the strip disposed above the supporting surface (see Figure 4) any writing in ink on the strip is not brought into contact with the supporting surface in connection with feed of the strip across the top face of the board.

The herein described writing device is essentially simple in construction and design and hence may be manufactured at an extremely low and reasonable cost. It has many capabilities of use and is characterized by the fact that the particular bearing arrangement for the supply and take-up spindles permits the spindles to be quickly and readily shifted into and out of place. The device is further characterized by the fact that it is durable and rugged while at the same time it is light in weight and may be readily carried or transported.

The invention is not to be understood as restricted to the details set forth since these may be modified within the scope of the appended claims without departing from the spirit and scope of the invention.

Having thus described the invention what I claim as new and desire to secure by Letters Patent is:

1. As a new article of manufacture, a writing device comprising a comparatively thin rectangular board, a materially thicker rectangular frame extending around, and depending from, the edges of the board, and embodying a pair of side mem-

bers with two spaced apart pairs of axially aligned bearings, and also embodying half round cross members extending between, and connected to, the ends of the side members, arranged so that the flat sides thereof are inwardly disposed, their rounded surfaces are outwardly disposed and their upper edges are flush with the top surface of the board, and forming with said board and side members a chamber that is closed except for the bottom, and a pair of transversely extending rotary spindles disposed for the most part in said chamber journalled in the two pairs of bearings, respectively, and adapted to support a strip of flexible writing material for feed around the rounded surfaces of the cross members of the frame and across the top face of the board.

2. As a new article of manufacture, a writing device comprising a rectangular board, a pair of laterally spaced side members connected to, and depending from, the side margins of the board and having in their central portions two opposed T-shaped openings with the intermediate parts thereof extending through the bottom faces of the side members and the ends of their cross parts defining two spaced apart pairs of axially aligned bearings, and a pair of rotary spindles beneath and extending transversely of the board, releasably journalled in the pairs of bearings, respectively, and adapted to support a strip of flexible writing material for feed across the top face of the board.

3. As a new article of manufacture, a writing device comprising a rectangular board, a rectangular frame extending around, and depending from, the edges of the board, and embodying a pair of side members having in the central portions thereof a pair of opposed T-shaped openings with the intermediate parts thereof extending through the bottom faces of the side members and the ends of their cross parts defining two spaced apart pairs of axially aligned bearings, said frame also embodying a pair of substantially half round cross members extending between and connected to the ends of the side members and arranged so that the flat sides thereof face inwards and their curved surfaces face outwards, and a pair of rotary spindles disposed beneath and extending transversely of the board, releasably journalled in the pairs of bearings, respectively, and adapted to support a strip of flexible writing material for feed around the cross members of the frame and across the top face of the board.

EWING M. JOHNSON.
